CHARLES P. HIDDEN, OF WINCHESTER, MASSACHUSETTS, ASSIGNOR TO THE LAMSON COMPANY, OF BOSTON, MASSACHUSETTS, A CORPORATION OF NEW JERSEY.

DESPATCH SYSTEM.

1,142,429.

Specification of Letters Patent. Patented June 8, 1915.

Application filed February 21, 1913. Serial No. 749,841.

To all whom it may concern:

Be it known that I, CHARLES P. HIDDEN, of Winchester, in the county of Middlesex and Commonwealth of Massachusetts, have 5 invented certain new and useful Improvements in Despatch Systems, of which the following is a specification.

This invention relates to despatch systems in general, and more particularly pneumatic 10 despatch systems, and has for one of its objects the provision of means in apparatus of this description for economizing power. I am aware that attempts have been made to save power in systems of this character and 15 in this connection I desire to direct attention to the U. S. Letters Patent to J. F. Skirrow, No. 1,045,205, dated November 26, 1912. Herein, time element means are provided for insuring the continuance of a flow of 20 air through a transmission tube for a determined interval of time; such interval being substantially fixed and invariable. I have found it, however, desirable, under certain conditions, that this time interval should be 25 made variable to a moderate degree in order to accommodate variations in pressure in the carrier transmitting pressure-fluid, *e. g.* compressed air. I have also found it desirable to provide in connection with a motor 30 or driven blower or pump, or other air displacing device, a reservoir within which the air may be stored and from which it may be withdrawn for carrier transmission purposes, as desired. This insures an immediate 35 delivery of pressure-fluid in adequate quantity without having to wait for the motor and blower to speed up to the point where the latter can deliver a volume of air under sufficient pressure to promptly start 40 the carrier upon its journey after it has been inserted in the receiving terminal. Where such a reservoir is not provided and where the blower is started substantially upon the admission of the carrier to said receiving 45 terminal, it necessarily follows that the pressure must be more or less increasingly but gradually built up until sufficient pressure is attained to start the carrier, and while said pressure is thus being developed a certain 50 seepage of air is apt to occur around the carrier so that while this interval is comparatively short, there is nevertheless a certain waste of power. On the other hand where a reservoir is used without any such 55 means as are hereinafter described for main-

taining pressure therein within determined limits, as the pressure-fluid is withdrawn from said reservoir, obviously the operating pressure of the system will gradually decrease. This results in a variable period of 60 transmission of the carrier through a given transmission tube and hence if time element means for controlling the flow of air from such reservoir be of such type as to render the system operative for a pre-determined 65 and fixed interval of time, again a certain small waste of power will almost inevitably result.

My system, while it employs a motor for generating mechanical power, does away 70 with the frequent stopping and starting of this motor incident to the Skirrow motor-operated system and hence effects a further saving of power. Since every time that the motor and blower are started inertia has to 75 be overcome. There is a further loss of power in the case of a system operated for a substantially pre-determined interval of time, where such system comprises looped together or connected transmission tubes, 80 where the air for conveying carriers in one direction is forced to first travel through a tube not directly used for out-going carriers from a given station and thereafter from 85 said tube to the tube which conveys said carriers from said station. This loss is due to the fact that the carrier propelling air current need flow but for a shorter interval for carriers traveling in one direction than for those traveling in an opposite direction, 90 so that with the time interval fixed the same for both, and that of sufficient duration for transmission purposes where the air flows around the loop, the said period is longer 95 than is really needed about one-half the time. Another aim of this present invention is therefore to eliminate even this waste.

It is primarily, therefore, the object of the present invention to provide such a system of fluid pressure generating and controlling apparatus as will effect an even greater economy of power than is possible with such constructions as are exemplified by Skirrow.

These and other objects of my invention will be hereinafter referred to and the novel elements and combinations of elements whereby said objects may be attained will now be more fully described and thereafter particularly pointed out in the claims appended hereto.

In the accompanying drawing which forms a part hereof, I have somewhat diagrammatically exemplified a preferred pneumatic despatch system of the kind in question.

I am aware however that many changes and modifications may be made herein without departing from the spirit of my invention and hence desire to be limited only by 10 the scope of said claims, broadly considered in the light of the disclosure.

Referring to the drawing, two stations A and B are therein shown as connected by transmission tubes 1 and 2. Tube 1 is provided with a receiving terminal 3 and a delivering terminal 4, while tube 2 is correspondingly provided with the receiving terminal 5 and delivering terminal 6. Terminals 3 and 5, and 4 and 6, respectively, 20 may be of substantially identical construction. Terminals 4 and 5 are connected by a loop 7, or in any other desired manner, so that air may flow from tube 1 into tube 2 via said terminals.

25 In the apparatus given by way of exemplification, compressed air is used to propel the carriers, this air being stored in a tank or reservoir 8 and passing thence to tube 1, when needed, through a pipe 9, a timing device, broadly designated 10 and hereafter more fully described, and a pipe 11, which delivers directly into the receiving terminal 3.

35 The particular construction of the delivering terminal 6 constitutes no part of the present invention but for convenience may be briefly described. Pivoted within this terminal at 12 is a bent lever 13 which has a slotted connection 14 with a valve 15; the 40 latter being pivoted at 16 to the lower portion of the terminal and being normally held closed by spring 17.

45 When a carrier strikes the lever 13 upon emerging into terminal 6 it swings said lever to the left and thereby opens valve 15, permitting said carrier to escape. Immediately thereafter spring 17 causes the valve 15 and lever 13 to resume their normal positions and the air subsequently entering terminal 50 6 from the transmission tube 2, as also the air in advance of said carrier, escapes through the exhaust pipe 18.

55 Reservoir 8 is normally filled with compressed air at a pressure ranging between determined limits; the compressed air being supplied to said reservoir through a pipe 19 leading from a blower 20, or the like; said blower being conveniently driven by an electric motor 21. The pipe 19 is provided 60 with a check valve 19' to prevent return or escape of air from the reservoir. Electric current for driving this motor is delivered from the positive lead 22 through a wire 23 and from thence, through connections hereinafter more particularly referred to, to a

solenoid 24. The current thereafter passes through a second solenoid 25, variable resistance 26, wire 27 to the motor 21 and from thence through a wire 28 to a switch arm 29.

70 The reservoir 8 is provided with a cylinder 30 which is in free communication with said reservoir and within this cylinder is a piston 31 which is normally pressed inwardly toward said receptacle by a spring 32, disposed within said cylinder. This spring, it may be here noted, may be given any desired initial tension by screwing in or out, as desired, the nut or spring abutment 33. The stem or rod 34 of the piston 35 31 carries upon its outer extremity a contact plate 35, which plate is adapted for engagement with the free end of the above mentioned switch arm 29, the latter being pivotedly mounted at 36.

85 When the pressure in the reservoir attains a determined amount it drives the piston 31 outwardly against the action of its spring and conversely when this pressure is below said amount, piston 31 together with contact 35 will be moved inwardly by said spring until contact 35 has not only engaged the extremity of switch arm 29 and swung the latter to the left but has also engaged a contact 37, thereby completing circuit 90 through the motor; current at such time passing from switch arm 29 through contact plate 35, contact 37 and wire 38 to a wire 39. Wire 39 leads to a contact 40 which is normally in engagement with a movable contact bar or plate 41, which latter is also normally in engagement with a contact 42. The current therefore passes through these contacts to a wire 43 and from thence back to the double pole switch 44 and out through 105 lead 45.

110 The energization of the motor circuit in the manner described effects the actuation of solenoid 24 above referred to, and the lifting of the core of this latter, short circuits the switch arm 29 and contacts 35 and 37; the motor circuit at such time being completed through contacts 46, 47 and 48 and from thence through wire 49 to wire 39 and out as before. This combination of elements, operating in the manner described, results in the continued driving of the motor after it has once been started, regardless of the development of sufficient pressure in the reservoir 8 to force piston 31 outwardly and thereby break the partial circuit through the switch arm 29. This switch arm is mechanically connected to a second switch arm 50 but is electrically insulated therefrom; movement of one of these arms in one direction or the other effecting a corresponding movement of the other arm. Switch arm 50 is adapted to be thrown into circuit with a battery 51, or other suitable source or current, and when the pressure in 120 125 130

the reservoir has attained its upper limit the piston 31 and contact 35 will at such time have been moved to the right, against the action of spring 32, until contact plate 35 engages a contact 52. At such time, also, it will further normally make contact with the free extremity of the arm 50; because in its previous movement to the left contact 35 will have swung the arm 29 to the left and thereby arm 50 correspondingly. To insure a proper disposition of the arms 29 and 50 in the positions into which they may be moved by the plate 35, one of these arms, *e. g.* 50, may be provided with a quadrant 54 the periphery of which may be suitably indented at two points for the reception of a spring pressed detent 55. Preferably, also, contacts 37 and 52 are resiliently mounted so as to insure proper contact. When the plate 36 so engages the arm 50 and contacts 52, current flows from the battery via wire 56 through a solenoid 57, wire 58 and a second solenoid 59, to the arm 50 and from thence through contact plate 35 and contact 52 back to the battery. This momentary closure of the battery circuit, however, by its energization of the solenoids 57 and 59, effects two results. In the first place it raises the contact bar or plate 41 which interrupts the flow of current through the motor, and this effects a de-energization of solenoid 24, which permanently opens the motor circuit until it is again re-established by the more or less momentary closure of said motor circuit when contact 35 engages contact 37 and arm 29 in the manner above described. The energization of solenoid 59 swings both switch arms 29 and 50 to the right and this interrupts the battery circuit, since the free extremity of arm 50 is thereby spaced from plate 35; hence solenoid 57 is de-energized almost immediately after the completion of the battery circuit and contact 41 again moves, by gravity, into engagement with contacts 40 and 42. Short as is this interruption of the motor circuit, however, it is sufficient to effect a permanent interruption thereof in manner aforesaid. Thus when the pressure in the reservoir is lowered to a determined amount by the withdrawal therefrom of air for successive transmission of carriers, the motor will be automatically started and said motor will continue in operation until the blower driven thereby has elevated the pressure in the reservoir to the pre-determined upper limit, whereupon, the motor will be automatically stopped.

The solenoid 59 is merely an added assurance that the battery circuit will be opened to save battery current after the solenoid 57 has been even momentarily energized, since if the quadrant be properly disposed and be provided with properly spaced indentations, the mere outward advance of

contact 35 may be made to first rotate the quadrant counter-clockwise until the detent rests upon the arcuate surface between the quadrant indentations, when, just as plate 35 engages contact 52, the spring pressed detent starts to slide down into the right hand indentation, thereby swinging arms 29 and 50 to the positions indicated in dotted lines and, of course, interrupting the battery circuit which has already performed its function. The omission of solenoid 59 however necessitates a closer setting or adjustment of contact 52 than is the case when solenoid 59 is provided.

I prefer to start the motor gradually; successively cutting resistance out of the motor circuit whenever said motor is started. To this end the solenoid 25 is caused to actuate the rheostat arm 60 and the lower extremity of the core of said solenoid 25 is connected to a piston 61 which is adapted for reciprocation in a dash pot or cylinder 62. The respective upper and lower extremities of said cylinder 62 are connected with check valves 63—63' which open outwardly so that when the piston 61 is ascending the air in advance thereof may freely be expelled through the upper check valve 63 and correspondingly when piston 61 is descending the air therebelow emerges through valve 63'. Timing valves 64—64' are also provided; by means of which the speed of ascent and also that of descent of said piston 61 may be regulated to a nicety. As a result of these provisions when the motor is started the resistance 26 may be cut out at any desired rate and conversely when the motor is stopped, if it be desired, such resistance may be cut in comparatively slowly. This results in a saving of wear and tear upon the motor and air displacing means; and since I prefer to so automatically start the motor each time only after a determined number of carriers have been transmitted, a material saving in power is effected, since power is more or less unnecessarily consumed, every time that the motor is started, in overcoming the inertia of the moving parts, etc.

Referring now to the combined valve and time element mechanism 10, it will be noted that the construction of this apparatus is exceedingly simple. It comprises a casing 66 within which reciprocates a double headed plunger, the lower head of which for convenience may be designated 67 and the upper head 68. The lower head 67 is materially larger in diameter than the upper head and the casing 66 is accordingly provided with two chambers, the lower, 69, neatly fitting head 67 and the upper chamber 70 correspondingly fitting head 68.

Head 68 serves as a valve for cutting off communication between pipes 9 and 10 when said head is in its lowermost position. The

space below the head 67 may be placed directly in connection with the reservoir 8 through the instrumentality of a pipe 71. In this pipe is a valve 72 which is normally held closed by means of a weight 73, or the like, but which may be opened upon the energization of a solenoid 74. This latter is in circuit with a battery 75, or other suitable source of electric current; being directly connected thereto, on one side, by a wire 76 and the other side of said solenoid being connected to a contact 77 by means of a wire 78. Adjacent contact 77 is a second contact 79 which is connected by a wire 80 and wire 81 to the other pole of the battery. The completion of this battery circuit is effected through the intermediary of a switch arm 82 which preferably is mounted upon the outer extremity of a spindle 83 which carries the valve 84 disposed at the carrier admitting opening of the terminal 3. As the terminals 3 and 5 are substantially identical in construction, switch arm 82 has been indicated only upon said terminal 5 since it is upon the outer side of the terminal casing. It is evident therefore that when the valve 84 is pressed inwardly as upon the insertion of the carrier into the receiving terminal, circuit across contacts 77 and 79 will be completed and solenoid 74 will be energized. This results in opening valve 72 and the pressure fluid passes from the reservoir 8 through pipe 71 into the space below the piston or head 67, promptly elevating the latter and thereby opening communication between passages 9 and 11. As long as solenoid 74 continues to be energized the double headed plunger will be held in its uppermost position but immediately the said solenoid is deenergized weight 73 closes valve 72 and the plunger commences to descend. The air trapped below plunger head 67, however, can only escape slowly through the air timing means, namely the restricted conduit 85; a needle valve 86 permitting of the regulation of this escape of air so that the speed of descent of the plunger valve 68 may be determined with considerable precision. I particularly desire to call attention, however, to the fact that the time or period during which this plunger valve is so descending is not a predetermined or fixed one but rather that it is dependent upon the pressure of the air issuing from the reservoir, because, when increased, the pressure upon the upper surface of the plunger head 67 will cause an accelerated descent of the plunger; while correspondingly as this pressure decreases, the speed of descent will be less. Furthermore it will be observed that the passage 87, which admits air under pressure from the reservoir 8 to and through the chamber 69, is angularly disposed with respect to the axis of the plunger, so that as the jet of

air emerges from said passage 87 it impinges upon the upper surface of the head 67 and it is obvious that if said air be delivered from the reservoir to the transmission tube under a relatively high speed the force or downward pressure exerted by the issuing jet of air upon said upper surface of the head 67 will be greater than when the speed of the air so delivered from the reservoir to the transmission tube is not so great. Thus both the pressure and the rate of flow of air delivered to the transmission tube coact to determine the speed of descent of the timing plunger. Immediately said plunger passes the port in the cylinder or casing 66 opening into pipe 11, of course, this flow of air from the reservoir will cease.

In a system, such as is shown by way of exemplification herein, the air for conveying carriers in one direction, *e. g.* from station B to station A, is first forced to travel through a tube 1, which is not directly used for the conveyance of out-going carriers from the station B and there is, of necessity, and especially where the transmission tubes are of considerable length, a material difference in the time during which air must be supplied from the reservoir or other source of pressure-fluid, between the time of transmitting a carrier between the stations A and B and between B and A; since in order to propel the carrier inserted at B to A the air must flow up around through pipe 1, terminal 4, loop 7 and only thereafter through terminal 5, transmission tube 2 and terminal 6. On the other hand, when a carrier is being sent from station A to station B the air enters immediately into the carrier conveying tube. In other words to transmit a carrier from B to A necessitates a compression of air in tube 1 to a pressure practically equal to that of the air delivered from the reservoir, before the carrier can be started upon its journey from station B to station A. Whereas when transmitting in a reverse direction there is no such necessity for compressing what may be a very extended column, so to speak, of air before the starting of the carrier on its journey can be effected.

If a predetermined and set interval of time during which pressure fluid will be supplied to the transmission line, be provided, regardless of the direction of transmission of carriers, there will, self evidently, be a waste of power when transmitting from, for example, station A to station B because this period of time will have to be sufficient to insure the transmission of carriers from B to A. I have accordingly provided means for insuring the delivery of pressure-fluid for one variable period of time (variable within substantially determined limits) when transmitting from station A to station B and have provided for

a somewhat longer variable period of time when transmitting carriers in a reverse direction.

When a carrier is inserted into terminal 5, at station B, the switch arm 82 closes the battery circuit across contacts 77' and 79' and current accordingly flows from the battery 75 through wire 81 contacts 77'-82 and 79', a wire 88, wire 89, solenoid 90, and through wire 91 back to the battery. This starts a secondary timing mechanism into operation, and the closure of circuit across contacts 77' and 79' thereby effects a practically simultaneous energization of not only this second solenoid 90, but further of the valve operating solenoid 74 in the manner hereinafter described.

Depending from the core of the solenoid 90 is a stem 92 which carries a piston 93 and at its lower extremity a bridge 94 adapted to complete circuit between a pair of contacts 95-96. The piston 93 is adapted to reciprocate in a cylinder 97; the lower extremity of said cylinder being connected to a check valve 98 the flap of which is pivotally mounted so that it may swing inwardly and freely admit air below piston 93 when the latter is ascending but which will check the flow of air from below said piston when the latter is descending. A set screw 99 mounted in the casing of the valve 98 provides means for cracking this valve, or in other words, very slightly raising it from its seat so that the air trapped below piston 93 may be allowed to seep around valve 98 at any desired rate whereby to time, subject to the provisions hereinafter referred to, the descent of said piston. The upper end of cylinder 97 is connected by means of a small pipe 100 with the timing conduit 85 of the mechanism 10, above referred to; and in this pipe 100 is disposed a valve casing 101; the valve 102 of which is pressed against its seat by a spring 103, or by gravity, if desired. While this valve has, hence, a bias for its closed position, an arm thereof, which projects upon the opposite side of the pivotal axis 104 of said valve, is adapted for engagement with the core of the solenoid 90 when said core is in its lowermost position, so that the weight of said core normally holds valve 102 open. As a result, the air escaping through conduit 85 passes through pipe 100 and escapes, normally, past valve 102. The moment, however, that solenoid 90 becomes energized, in the manner above described, valve 102 closes and the air passing through pipe 100, instead of escaping immediately to the atmosphere passes on through casing 101 and enters cylinder 97 above piston 93. As this air accumulates in this space, it presses said piston down with more or less force according to the speed of descent of the piston head 67 in the timing mechanism 10. Therefore this second tim-

ing instrumentality is governed or controlled by the first. Now, the upward movement of stem 92, by the energization of solenoid 90, due to the closure of circuit at 77'-79' in the manner above described, 70 brings the bridge 94 into engagement with contacts 95 and 96 and completes a circuit through wires 105, 106, 78 and 76, which energizes solenoid 74. The continued upward movement of the bridge 94 may thereafter either withdraw said bridge out of engagement with contacts 95 and 96, or may not, as desired. It is preferable however to draw the bridge 94 out of engagement with contacts 95 and 96 in order to save battery 80 current, especially after the insertion of the carrier past valve 84. If bridge 94 be above contacts 95-96, the battery circuit will be completely opened and solenoid 74 will be deenergized which permits weight 73 to close valve 72 and the timing mechanism 10 starts to time. Valve 102 will however be closed and piston 93 will be more or less slowly descending. During this interval, air from below the head 67 will pass into cylinder 97 and more or less accelerate the speed of descent of piston 93; this variation in speed of said piston depending upon the pressure of air in reservoir 8 and the rate of flow of said air through passage 87. 95

As bridge 94 continues to descend it will again close the battery circuit across contacts 95-96 and this will momentarily re-energize solenoid 74 and re-time mechanism 10. Immediately after this, valve 102 will 100 be opened, while bridge 94 will be moved out of engagement with contacts 95 and 96; again interrupting the battery circuit. Thereafter the timing mechanism 10 will operate exactly as if it has been actuated from station A. It will hence be observed that by thus inserting a carrier in terminal 5, at station B, the timing mechanism 10 is started, permitting the pressure-fluid to be freely delivered to the transmission line; but that after the lapse of a period determined by the rate of descent of piston 93 and before the flow of air from reservoir 8 is interrupted by valve or piston head 68, said timing mechanism 10 will be automatically 110 retimed and thereafter allowed to automatically cut off communication with the source of fluid pressure substantially exactly as in the case where a carrier is being sent from station A to station B. It will further be 115 observed that I am thus enabled to add to the length of time required to send a carrier from station A to station B, a sufficient additional period of time to allow for the transmission of air through tube 1 before 120 starting the carrier at B toward A; and that both of these periods of time are subject to variations in pressure in the reservoir or 125 source of pressure-fluid and also to the rate at which the pressure-fluid is delivered to 130

the transmission line. Practically the utmost economy is therefore effected by the present system; substantially every factor that would result in a loss of efficiency being considered.

Considering the operation of the system as a whole, in brief therefore, the motor which operates the blower which stores the pressure-fluid in the reservoir is rendered operative but once for substantially a given number of carrier transmissions; and when it is so operated it is started and stopped most efficiently. When the pressure in the reservoir attains a pre-determined amount this 10 motor is automatically stopped and when the lower pressure limit allowed for the operation of the system is reached, said motor is automatically again started.

The flow of pressure fluid from the reservoir is economically and efficiently governed 20 through the instrumentality of the mechanism 10. The auxiliary time element mechanism comprising piston 93, operates, in the manner aforesaid, to automatically add the 25 time needed for transmission in one direction over that required for carrier transmission in an opposite direction; and even this additional time is subject to variations in the pressure and rate of flow of the pressure 30 fluid into and through the transmission tubes.

While I have shown electrically operated devices, namely solenoids, in the several places where such devices have been indicated, it is of course obvious that other instruments may be employed. I further desire to direct attention to the fact that while I prefer to combine the valve or corresponding device which controls the flow 35 of pressure fluid into the transmission tubes, so that it is directly and integrally attached 40 to a part of the time element mechanism, it is by no means essential that such construction be employed, since anyone skilled in the art should be able to substitute combinations 45 of other elements adapted to perform the functions which mechanism 10 is intended to accomplish. In like manner various other changes and modifications may be made throughout the system without, as above 50 stated, departing from the spirit of my invention. Further, while the various herein described apparatus and combinations of elements are particularly adapted to a pressure system and the invention has been 55 closed in connection with such a system, I do not desire to be limited in any way, other than where in certain of the appended claims, such a pressure system is unequivocally indicated.

60 The saving of power effected by the present invention renders it of particular value in connection with despatch tube systems having transmissions tubes of large diameter. The fact, too, that while the mechanism 65 10 is dependent upon both the flow

and pressure of air delivered through the transmission tube, it is nevertheless adapted to be re-timed for successive carrier insertions without rendering operative the air impeding means or valve 68 to stop said flow 70 of air, is of very considerable importance. The length of the additional time provided by the secondary timing means will also, 75 obviously, be influenced by the extent and disposition of the contacts 95-96.

The provision of time element means for establishing a more protracted carrier propelling effort for the transmission of carriers from one station to another than for the transmission of carriers from said other 80 to said one, is believed to be broadly new, and except where the claims drawn to combinations including such means are specifically limited to pneumatic despatch apparatus, they are not to be regarded as limited in 85 any way to the apparatus particularly described. Even in pneumatic despatch systems, in general, the aid received from gravity or other source of power may advantageously be taken account of by means 90 of differential timing mechanism such, for example, as that herein given by way of exemplification.

Similar remarks apply to the slowing down or retarding of the primary timing 95 mechanism 10 by the closure of valve 102 when the supplemented or secondary timing device is actuated; and, correspondingly, the acceleration of the secondary timing device by the pressure exerted upon the piston 100 thereof through the intermediacy of said primary timing device. Further, to the best of my knowledge it is broadly new in despatch systems to provide means for automatically re-timing a timing device which 105 controls the duration of the carrier propelling effort.

I am aware that in the system described in the aforesaid patent to Skirrow, the introduction of a second carrier following a first, re-times the timing mechanism, but such system obviously does not provide automatic means such as have just been referred to, the second carrier being inserted through 110 the intermediacy of an operator who thereby immediately retimes the mechanism. This automatic re-timing or time-extension feature should prove of especial value where, for example, the distance between stations 115 is relatively great; even when the time of transmission both ways is substantially the same. Thus, in very long transmission lines it is possible by means of this automatic and successive re-timing of a timing device, to extend to practically any desired extent the 120 period during which energy or power for propelling carriers along their guide-ways, e. g. tubes, may be expended, a plurality of timing devices being, in effect, relayed to 125 effect this end.

Having thus described my invention what I claim is:

1. In a pneumatic despatch system, the combination of a receptacle adapted to contain air at a pressure different from that of the surrounding atmosphere, means for creating this difference in pressure, means for controlling the last mentioned means whereby to insure said difference in pressure being maintained adequate for carrier transmission purposes, a tube for transmitting carriers, and means, co-acting with said tube for rendering said difference in pressure effective for carrier transmission purposes, for a normally limited interval of time, said last mentioned means including a time element mechanism for automatically limiting the carrier transmitting flow of air after the lapse of a variable period of time sufficient to transmit a carrier effectively through said tube under the pressure conditions present at such time in the system, said time element mechanism provided with means for varying said time period substantially in accordance with the operating pressure in said system. 75
2. In a pneumatic despatch system, the combination of a receptacle adapted to contain air at a pressure different from that of the surrounding atmosphere, means for creating this difference in pressure, means for controlling the last mentioned means whereby to insure said difference in pressure being maintained adequate for carrier transmission purposes, a tube for transmitting carriers, and means, co-acting with said tube for rendering said difference in pressure effective for carrier transmission purposes, for a normally limited interval of time, said last mentioned means including a time element mechanism for automatically limiting the carrier transmitting flow of air after the lapse of a variable period of time sufficient to transmit a carrier effectively through said tube under the pressure conditions present at such time in the system, said time element mechanism provided with means for varying said time period substantially in accordance with the operating pressure in said system. 80
3. In a pneumatic despatch system, the combination of a receptacle adapted to contain air at a pressure different from that of the surrounding atmosphere, means for creating this difference in pressure, means for controlling the last mentioned means whereby to insure said difference in pressure being maintained adequate for carrier transmission purposes, a tube for transmitting carriers, and means, co-acting with said tube for rendering said difference in pressure effective for carrier transmission purposes, for a normally limited interval of time, said last mentioned means including a time element mechanism for automatically limiting the carrier transmitting flow of air after the lapse of a variable period of time sufficient to transmit a carrier effectively through said tube under the pressure conditions present at such time in the system, said time element mechanism provided with means for varying said time period substantially in accordance with the speed of flow of air through said tube. 85
4. In a pneumatic despatch system, the combination of a transmission tube, a station having means for permitting the introduction of carriers into said tube, a compressed air supply, a valve for controlling the flow of air from said supply through said tube, means for opening and for controlling the subsequent closure of said valve, said last mentioned means including a timing means controlling said valve closure and operating dependently of the rate of movement of the air moving through said tube, and means, operable from said station, for rendering operative the valve opening and timing means. 90
5. In a pneumatic despatch system, the combination of a transmission tube, a station having means for permitting the introduction of carriers into said tube, an air supply, comprising a reservoir and means for automatically charging said reservoir with compressed air from time to time in accordance with the demands of said system, and means for conserving air from said supply comprising a valve for controlling the flow of said air through said tube, means for opening and for controlling the subsequent closure of said valve, said last mentioned means including variably acting timing means controlling said valve closure and having provisions to cause said timing means to operate dependently of the pressure of the air moving through said tube, and means, operable from said station, for rendering operative said valve opening and timing means. 95
6. In a pneumatic despatch system, the combination of a transmission tube, a plurality of stations each having means for permitting the introduction of carriers into said tube, a compressed air supply, a valve for controlling the flow of air from said supply through said tube, means for opening and for controlling the subsequent closure of said valve, said means including variably acting pressure controlled timing means controlling said valve closure and operating dependently of the pressure of the air moving through said tube, and means, operable from any one of said stations, for rendering operative said valve opening and timing means, at least one of said stations being relatively remote from said valve. 100

tion having means for permitting the introduction of carriers into said tube and means for establishing for a normally limited period of time, a carrier transmitting flow of air through said tube, said means including a part adapted to normally impede said flow, means for rendering said air impeding part substantially inoperative, timing means controlling the return of said part to its normal position and operating dependently of the pressure of said air, and means, operable from said station, for rendering operative said two last mentioned means, said timing means adapted to be re-timed for the transmission of successive carriers introduced into said system during the time that said timing means is operative, and said air impeding part being adapted to remain substantially wholly inoperative when said timing means is so re-timed and being out of the path of travel of said air at such times.

8. In a pneumatic despatch system, the combination of a transmission tube, a plurality of stations having means for permitting the introduction of carriers into said tube, and means for establishing, for a normally limited period of time, a carrier transmitting flow of air through said tube, said means including a part adapted to normally impede said flow, means for rendering said part substantially inoperative, variably acting timing means controlling the return of said part to its normal position and operating dependently of the pressure of said air, said timing means having a movable controlling element thereof disposed for contact with the air current and variably movable in accordance with the variations in pressure of said air, and means, operable from any one of said stations, for rendering operative said two last mentioned means, said timing means adapted to be re-timed for the transmission of successive carriers introduced into said system during the time that said timing means is operative, said air impeding part remaining substantially wholly inoperative when said timing means is so re-timed.

50 9. In a pneumatic despatch system, the combination of a carrier, with a looped transmission tube connecting a plurality of stations and means for establishing for a normally limited period, a carrier propelling current of air in said tube, said means including timing means for controlling the duration of said current, said mechanism having provisions, substantially independent of the travel of carriers, for insuring a longer flow of air for transmitting carriers from one of said stations to another station than for transmitting carriers from said other to said one.

65 10. In a pneumatic despatch system, the combination of a carrier, with a transmis-

sion tube connecting a plurality of stations and means for establishing, for a normally limited period, a carrier propelling current of air in said tube, said means including a timing mechanism for controlling said last mentioned means, said mechanism having provisions, substantially independent of the travel of carriers, for insuring a longer flow of air for transmitting carriers from one of said stations to another station than for transmitting carriers from said other to said one.

11. In a pneumatic despatch system, the combination of a carrier, with pneumatic transmission means connecting a plurality of stations and means for establishing, for a normally limited period, a carrier propelling current of air in said transmission means, said means including a timing mechanism for controlling said current of air, said mechanism having provisions for insuring a longer flow of air for transmitting carriers from one of said stations to another than for transmitting carriers from said other to said one.

12. In a despatch system, the combination of a carrier, with carrier guiding means connecting a plurality of stations and means for establishing, for a normally limited period, a carrier propelling effort for transmitting carriers from one of said stations to another, said means including a timing mechanism for controlling said effort, said mechanism having provisions for insuring a more protracted effort for transmitting carriers from one station to another than for transmitting carriers from said other to said one.

13. In a despatch system, the combination of a carrier, with carrier guiding means connecting a plurality of stations and means for establishing, for a normally limited period, a carrier propelling effort for transmitting carriers from one of said stations to another, said means including timing mechanism, operable mechanically, at least in part, for controlling said effort establishing means, said mechanism having provisions for insuring a more protracted effort for transmitting carriers from one station to another than for transmitting carriers from said other to said one.

14. In a despatch system, the combination of a carrier, with carrier guiding means connecting a plurality of stations, and means for establishing, for a normally limited period, a carrier propelling effort for transmitting carriers from one of said stations to another, said means including timing mechanism, operable electrically, at least in part, for controlling said effort, said mechanism having provisions for insuring a more protracted effort for transmitting carriers from one station to another than for transmitting carriers from said other to said one.

15. In a despatch system, the combination

of a carrier, with carrier guiding means connecting a plurality of stations and means for establishing, for a normally limited period, a carrier propelling effort for transmitting carriers from one of said stations to another, said means including differential timing mechanism for automatically permitting the expenditure of more power for carrier transmission purposes for carriers traveling in one direction than for carriers traveling in another direction.

16. In a despatch system, the combination of a carrier, with carrier guiding means connecting a plurality of stations and means for establishing, for a normally limited period, a carrier propelling effort for transmitting carriers from one of said stations to another, said means including differential timing mechanism for permitting the expenditure of more power for carrier transmission purposes for carriers traveling in one direction than for carriers traveling in another direction, said mechanism having provisions for varying the time determined thereby substantially according to the amount of power available to be expended.

17. In a despatch system, the combination of a carrier, with carrier guiding means connecting a plurality of stations and means for establishing, for a normally limited period, a carrier propelling effort for transmitting carriers from one of said stations to another, said means including differential timing mechanism for permitting the expenditure of more power for carrier transmission purposes for carriers traveling in one direction than for carriers traveling in another direction, said mechanism having provisions for varying the time determined thereby substantially according to the carrier propelling effort possible to be established at such time.

18. In a despatch system, the combination of a carrier, with carrier guiding means connecting a plurality of stations and means for establishing, for a normally limited period, a carrier propelling effort for transmitting carriers from one of said stations to another, said means including a plurality of interconnected timing devices adapted to co-act to variably control the expenditure of power for carrier transmission purposes in accordance with service requirements of said system.

19. In a despatch system, the combination of a carrier, with carrier guiding means connecting a plurality of stations and means for establishing, for a normally limited period, a carrier propelling effort for transmitting carriers from one of said stations to another, said means including a plurality of interconnected timing devices adapted to co-act to variably control the expenditure of power for carrier transmission

purposes in accordance with the service requirements of said system, said devices provided with means for effecting a successive actuation thereof.

20. In a despatch system, the combination of a carrier, with carrier guiding means connecting a plurality of stations and means for establishing, for a normally limited period, a carrier propelling effort for transmitting carriers from one of said stations to another, said means including a plurality of timing devices for controlling the expenditure of power for carrier transmission purposes in accordance with the service requirements of said system, and connections between said timing devices for determining the rate of actuation of one of said devices by the rate of actuation of another.

21. In a despatch system, the combination of a carrier, with carrier guiding means connecting a plurality of stations and means for establishing, for a normally limited period, a carrier propelling effort for transmitting carriers from one of said stations to another, said means including a plurality of timing devices for controlling the expenditure of power for carrier transmission purposes in accordance with the service requirements of said system, and connections between said timing devices for controlling the rate of actuation of one of said devices by the actuation of another of said devices.

22. In a despatch system, the combination of a carrier, with carrier guiding means connecting a plurality of stations and means for establishing, for a normally limited period, a carrier propelling effort for transmitting carriers from one of said stations to another, said means including a plurality of timing devices for controlling the expenditure of power for carrier transmission purposes, and connections between said timing devices for retarding the actuation of one of said devices substantially in accordance with the requirements of service conditions in said system.

23. In a despatch system, the combination of a carrier, with carrier guiding means connecting a plurality of stations and means for establishing, for a normally limited period, a carrier propelling effort for transmitting carriers from one of said stations to another, said means including a timing device provided with means for slowing down the normal actuation thereof for a period of limited duration in accordance with the requirements of service conditions in said system.

24. In a despatch system, the combination of a carrier, with carrier guiding means connecting a plurality of stations and means for establishing, for a normally limited period, a carrier propelling effort for

transmitting carriers from one of said stations to another, said means including a timing device provided with mechanism for temporarily slowing down the normal actuation thereof in accordance with the requirements of service conditions in said system.

25. In a despatch system, the combination of a carrier, with carrier guiding means, a source of power for transmitting carriers in the direction of the length of said guiding means, means, including a timing mechanism for controlling the delivery of said power from said source, and means, governed by the rate at which power is delivered from said source of power, for automatically accelerating the action of said timing mechanism.

26. In a despatch system, the combination of a carrier, with carrier guiding means, means for establishing a carrier propelling effort for transmitting carriers in the direction of the length of said guiding means, means for limiting the duration of said effort, including a primary and a secondary timing means and connections between said means for re-timing said primary means through the intermediacy of said secondary means.

27. In a despatch system, the combination of a carrier, with carrier guiding means extending between two stations, means for establishing a carrier propelling effort for transmitting carriers in the direction of the length of said guiding means, means, including two timing mechanisms, for limiting the duration of said effort, means at one of said stations for rendering both of said mechanisms operative and means at the other of said stations for rendering one of said mechanisms operative.

28. In a despatch system, the combination of a carrier, with carrier guiding means extending between two stations, means for establishing a carrier propelling effort for transmitting carriers between said stations, means, including a timing mechanism, for limiting the duration of said effort, and means, operable from one of said stations, for extending the time during which said effort is exerted.

29. In a despatch system, the combination of a carrier, with carrier guiding means extending between two stations, means for establishing a carrier propelling effort for transmitting carriers between said stations, means, including a timing mechanism, for limiting the duration of said effort and automatic means, initially operable from one of said stations, for extending the time during which said effort is exerted.

30. In a despatch system, the combination of a carrier, with carrier guiding means extending between two stations, means for establishing a carrier propelling effort for

transmitting carriers between said stations, means, including a timing mechanism, for limiting the duration of said effort, and automatic means, initially operable from one of said stations, for varying the time during which said effort is exerted.

31. In a despatch system, the combination of a carrier, with carrier guiding means extending between two stations, means for establishing a carrier propelling effort for transmitting carriers between said stations, means, including a timing mechanism, for limiting the duration of said effort, and means, dependent upon the efficiency of said effort and independent of said carrier for automatically extending the time during which said effort is exerted.

32. In a despatch system, the combination of a carrier, with carrier guiding means extending between two stations, means for establishing a carrier propelling effort for transmitting carriers between said stations, means, including a timing mechanism, for limiting the duration of said effort, and means for automatically re-timing said timing means after the lapse of a material interval of time subsequent to the initial subjection of said carrier to said effort, said automatic means adapted to operate independently of the travel of said carrier.

33. In a despatch system, the combination of a carrier, with carrier guiding means extending between two stations, means for establishing a carrier propelling effort for transmitting carriers between said stations, means, including a timing mechanism, for limiting the duration of said effort, and auxiliary means for re-timing said timing means after the lapse of an interval of time, dependent upon operating conditions in said system, subsequent to the initial subjection of said carrier to said effort.

34. In a despatch system, the combination of a carrier, with carrier guiding means, means for establishing a carrier propelling effort for transmitting carriers in the direction of the length of said guiding means, means, including a timing mechanism, for limiting the duration of said effort, and means for automatically re-timing said timing means after the lapse of a material interval of time subsequent to the initial subjection of said carrier to said effort.

35. In a despatch system, the combination of a carrier, with carrier guiding means connecting a plurality of stations, means for establishing a carrier propelling effort for transmitting carriers from one of said stations to another, two interconnected timing devices for controlling the expenditure of power for carrier propelling purposes in accordance with the service requirements of said system, said system having provisions for varying the rates of actuation of both of said timing devices.

36. In a pneumatic despatch system, the combination of a transmission tube, a station having means for permitting the introduction of carriers into said tube, an air supply, a valve for controlling the flow of air from said supply through said tube, means for opening and for controlling the subsequent closure of said valve, said last mentioned means including a timing means controlling said valve closure and operating independently of the rate of movement of the air moving through said tube, a movably mounted part of said valve opening and con-

trolling means being directly in the path of the current of said air and subject to the pressure of said air exerted upon said part, and means, operable from said station, for rendering operative the valve opening and timing means.

In testimony whereof I have affixed my signature, in the presence of two witnesses.

CHARLES P. HIDDEN.
